UNITED STATES PATENT OFFICE.

JULES DESCHAMPS, OF PARIS, FRANCE.

AUTOMATIC ELECTRIC DESPATCH SYSTEM.

1,078,035.

Specification of Letters Patent.

Patented Nov. 11, 1913.

Original application filed January 26, 1912, Serial No. 673,511. Divided and this application filed October 28, 1912. Serial No. 728,253.

To all whom it may concern:

Be it known that I, JULES DESCHAMPS, a citizen of the Republic of France, residing at Paris, France, have invented certain new and useful Improvements in Automatic Electric Despatch Systems; and I do hereby declare the following to be a full, clear, and exact description of the invention, such as will enable others skilled in the art to 5 which it appertains to make and use the same.

The present invention has relation to certain improvements in the system of automatic operation of electric cars set forth in my 15 pending application for Letters Patent of the United States, Serial Number 673,511, filed January 26, 1912, wherein the stopping, retarding, starting and acceleration of electric cars is controlled automatically by 20 suitable stationary current-modifying devices placed along the track.

This application is a division of my above named earlier application for patent.

In the automatic car operating system referred to the cars receive the impelling current from sectional feeding conductors placed along the line of travel, each section being arranged to supply the current through suitable resistances or other current modifiers, whereby the energy supplied along each given portion of the line is made proportional to the conditions existing in that portion of the line. It is clear that, in a system of this kind, it is desirable that accidental collisions between successive cars or trains should be avoided, and the present invention relates particularly to means whereby this end is carried out automatically.

Described in broad terms, the improved 40 system in question comprises a railway of the class described wherein the closing of any one section of operating circuit is made to automatically modify the degree of energy transmittable to a preceding section of 45 circuit or to a following section, or both; whereby, when two cars are near enough together to make it dangerous for them to come nearer, the following car shall be slowed up, or the car in front shall be accelerated, or both of these effects shall take place.

My invention may be used either with di-

rect or alternating current and the modification of operating conditions may consist in changes of voltage or resistance or in 55 changes in frequency where alternating currents are used.

In the following description, I have set forth certain preferred embodiments of the invention as carried out in that form thereof 60 wherein the motors on the cars are supplied with separate exciting currents for the field magnets (inductors) and armatures respectively; but it is to be understood that my broader claims are not confined in their 65 scope to systems presenting these specific conditions.

In the accompanying drawings Figure 1 is a diagram of a preferred embodiment of my invention, and Fig. 2 is a similar view of 70 a portion of such a system wherein it is found expedient to apply a braking action to the following car.

In the particular preferred form shown in the drawings the cars are supposed to be 75 driven by two main generators, preferably of different potentials. These generators may feed the whole or only a part of the total line.

The generator *a* is a high tension generator 80 for the armatures *d*₁ *d*₂ of the car motors, and the generator *b* is a relatively low tension generator for the inductors of field magnets *e*₁ *e*₂. One terminal of generator *a* is connected to the main feed wire 85 or lead *L*, the opposite terminal being preferably connected to the return rails, as shown. One terminal of the generator *b* is connected to the main lead *T*, while the return rails are connected to the opposite terminal of said generator. 90

As shown in Fig. 1, the various field magnet coils *e*₁ *e*₂, etc., of the car motors receive current by suitable shoes or trolleys from successive insulated feeding sections 95 *T*₁ *T*₂, etc., which are supplied from the main lead *T*, and the current returns in a well known manner from each field coil through the wheels and tracks. It is also clear that each armature *d*₁, *d*₂, etc., on the 100 various cars receive current from successive insulated feeding circuits *S*₁, *S*₂, and that the armature circuits are also closed through the wheels and tracks. Of course a special

return wire may be substituted for the car tracks or ground if desired.

My invention comprises means whereby, as shown, as circuit is closed through a given sectional feed wire, automatic means are at once energized which act suitably to modify the circuit conditions in adjacent sections. In the preferred form shown the field magnet circuits on each section affect circuit conditions on the feed-section ahead of a given car, while the armature circuits affect circuit conditions on the following feed-section. A double automatic action is thus secured. It is to be understood that I claim each of these actions in this connection, and that it is not essential to my invention that the two should be used together. It is also to be understood that I do not confine myself to the particular forms of automatic circuit-modifying devices indicated.

In the particular example diagrammatically shown in Fig. 1 the car or train on section S_2 is supposed to be normally somewhat retarded by introduction of a fixed resistance A_2 , whereby the voltage across the armature terminals is lowered. Current is normally led through the resistance A_2 by a wire connected to the main armature lead L at the point f_2 , and by a low resistance short circuit around the auxiliary resistance coil m_2 , which short circuit includes a lever l normally maintained in the position l_1 by the spring p . If, however, there is a car or train on the section in front, as shown in Fig. 1, a circuit is closed from f_1 (on the main lead L) through the coils of an electromagnet o , to the sectional lead S_1 of the next section forward. This wire may represent either the conductor carrying the impelling current to the armature d_1 or a shunt circuit, according to circumstances. In other words the magnet o may be either in series or shunt with respect to the armature d_1 . It is obvious, then, that, so long as this magnet circuit exists, the magnet o will attract the armature m carried by the lever l , and will open the short circuit around the resistance m_2 by causing said lever to assume the position l_2 . This latter resistance will then assume its auxiliary function, and will aid in cutting down the voltage across the terminals of the motor armature d_2 , thus retarding the following car to that extent.

The field magnet e_1 of the front car is fed from the section T_1 which normally receives its current through a short circuit around the resistance n_1 , which short circuit includes the lever k normally in the position k_1 . The electromagnet o_1 , similarly to magnet o , is in a shunt or a series connection with the feeding current through the following field magnet e_2 , and therefore, so long as this latter circuit exists, the voltage across the terminals of the forward field magnet e_1 is

reduced by the resistance n_1 . This, of course, weakens the field magnet of the forward motor, and accelerates movement of the car. The two operations thus described serve to enlarge the separation between the cars when they approach each other too nearly.

My invention is not limited to an arrangement in which the automatic circuit modifier for any one section T_1 or T_2 is operated by closure of circuit to the next adjacent section wire. Cases may occur wherein it would be desirable to retard or accelerate a car separated from another by a distance greater than that between adjacent sections, and my invention is applicable to such cases.

In some instances (as where a car is descending a slope or is approaching a station) it is well to place its motor armature on a closed circuit independent of the generator, thereby establishing a braking action, and in Fig. 2 I have shown an example of a means within my invention, whereby a following car may be retarded automatically while being braked in the manner just mentioned. In this figure, the following car has its armature circuit closed through the normal resistance composed of the sum of the resistances B_2 and R_2 , and the lever l of the automatic circuit modifier is in the retracted position l_2 . When, however, the magnet coils o are energized by closure of a shunt or series circuit to a preceding armature sectional feed T_1 , the magnet draws this lever into the position l_1 , and the auxiliary resistance coil R_2 is short-circuited, thereby increasing the current through the armature of the following car, and increasing the braking or retarding effect.

The automatic circuit modifiers shown are simply examples of forms suited to the particular system of electrical distribution assumed for the drawings of this case.

It will, of course, be understood that, where other distribution systems are adopted suitable modifications of my devices will be adopted; all within the spirit and scope of this invention.

What I claim is—

1. An electric despatch system comprising in combination electric cars, two mutually insulated feed sections therefor, an automatic circuit modifier adapted to modify the motor circuit conditions on one of said sections and a circuit for affecting said modifier adapted to be closed through a car on the other of said sections, substantially as described.

2. An electric despatch system comprising in combination electric cars, two mutually insulated feed sections therefor, an automatic circuit modifier adapted to modify the energizing circuit of a motor on one of said sections, and a circuit for affecting said mod-

6 classifier adapted to be closed through a car on the other of said sections, substantially as described.

3. An electric despatch system comprising in combination electric cars, two mutually insulated feed sections therefor, an automatic circuit modifier adapted to modify the armature circuit of a motor on one of said sections, and a circuit for affecting said modifier adapted to be closed through a motor on the other of said sections, substantially as described.

4. An electric despatch system comprising in combination electric cars, two mutually insulated feed sections therefor, an automatic circuit modifier adapted to modify the field magnet circuit of a motor on one of said sections, and a circuit for affecting said modifier adapted to be closed through a motor on the other of said sections, substantially as described.

5. An electric despatch system comprising in combination electric cars, separate main leads for the field magnets and armatures of the car motors respectively, a pair of sectional wires for a leading car, a separate pair of sectional wires for a following car, an automatic circuit modifier controlling the circuit conditions of one of said following car wires, and electrical means for governing said circuit modifier in circuit with one of said leading car wires, substantially as described.

6. An electric despatch system comprising in combination electric cars, separate main leads for the field magnets and armatures of the car motors respectively, a pair of sectional wires for a leading car, a separate pair of sectional wires for a following car, an automatic circuit modifier controlling the circuit conditions of one of said leading car wires and electrical means for governing said circuit modifier in circuit with one of said following car wires, substantially as described.

7. An electric despatch system comprising in combination electric cars, separate main leads for the field magnets and armatures of the car motors respectively, a pair of sectional wires for a leading car, a separate pair of sectional wires for a following car, an automatic circuit modifier controlling the circuit conditions of one of said following car wires, a second automatic circuit controller controlling the circuit conditions of one of said leading car wires, electrical means in circuit with one of said leading car wires for governing said first named circuit modifier, and electrical means in circuit with one of said following car wires for governing said second named circuit modifier, substantially as described.

8. An electrical despatch system comprising in combination cars having electric prop-

elling motors, a main lead and sectional wires for feeding the field magnets of said motors, a separate main lead and sectional wires for feeding the armatures of said motors, a generator connected to said first named main lead, a generator connected to said second named main lead, feeding circuits from the armature main lead to each armature sectional wire, an automatic circuit modifier for one of said feeding circuits, and an operating circuit for said circuit modifier, said operating circuit joining the armature main lead to an armature sectional wire other than that which is controlled by the corresponding circuit modifier, substantially as described.

9. An electric despatch system comprising in combination cars having electric propelling motors, a main lead and sectional wires for feeding the field magnets of said motors, a separate main lead and sectional wires for feeding the armatures of said motors, a generator connected to said first named main lead, a generator connected to said second named main lead, feeding circuits from the field magnet main leads to each field magnet sectional wire, an automatic circuit modifier for one of said feeding circuits, and an operating circuit for said modifier joining the field magnet main lead to a field magnet sectional wire other than that which is controlled by the corresponding modifier, substantially as described.

10. An electric despatch system comprising in combination electric cars, two mutually insulated feed sections therefor, means for conveying electric current to one of said feed sections including an auxiliary resistance, means for normally maintaining a short circuit around said resistance, an electro-magnet adapted to open said short circuit when energized, and a circuit including the coils of said electro-magnet which circuit is connected with the other of said feed sections and is adapted to be closed through a car energized through said section, substantially as described.

11. An electric despatch system comprising in combination electric cars following one another, two mutually insulated feed sections, one for a leading and the other for a following car, means for conveying electric current to the following feed section including an auxiliary resistance, means for normally maintaining a short circuit around said resistance, an electro-magnet adapted to open said short circuit when energized, and a circuit including the coils of said electro-magnet which circuit is connected with the leading feed section, substantially as described.

12. An electric despatch system comprising in combination electric cars following one another, two mutually insulated feed

sections, one for a leading and the other for a following car, means for conveying electric current to the leading feed section including an auxiliary resistance, means for normally maintaining a short circuit around said resistance, an electro-magnet adapted to open said short circuit when energized, and a circuit including the coils of said electro-magnet which circuit is connected with the

following feed section, substantially as described. 10

In testimony whereof, I affix my signature, in presence of two witnesses.

JULES DESCHAMPS.
